CLAIM

The ornamental design for an embossing roller with fine dots as shown and described.

DESCRIPTION

FIG. 1 is a top perspective view of an embossing roller with fine dots showing the new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is an enlarged view of the area marked by the number 8 in FIG. 1, showing the fine dots of the design.

The broken lines indicate portions of the embossing roller with fine dots that form no part of the claimed design.
